UNITED STATES PATENT OFFICE.

FRED A. LEIGH, OF DETROIT, MICHIGAN.

ROTARY PUMP.

Application filed February 13, 1922, Serial No. 536,112. Renewed February 11, 1924.

To all whom it may concern:

Be it known that I, FRED A. LEIGH, a citizen of the United States of America, residing at Detroit, in the county of Wayne and State of Michigan, have invented certain new and useful Improvements in Rotary Pumps, of which the following is a specification, reference being had therein to the accompanying drawings.

10 This invention relates to rotary pumps, and more particularly to that type wherein a rotor is eccentrically disposed in a cylinder or chamber for inlet and outlet connections, and the rotor provided with pivoted 15 pistons or liquid or fluid shifting members which transfer the liquid or fluid from the inlet connection to the cylinder or chamber to the outlet connection thereof.

My invention aims to provide a rotary 20 pump of the above type wherein a rotor has pistons or liquid or fluid shifting members of novel design, said pistons being automatic in their action and highly efficient for moving a body of liquid or fluid; in connection 25 with the pistons novel packing is employed to insure a positive contact between movable parts of the pump, so that leakage is reduced to a minimum and a maximum pumping suction of the pump at all times attained.

30 My invention further aims to provide a rotary pump structure wherein a cylinder has eccentrically disposed end flanges provided with concentric seats, said seats being eccentrically disposed relative to the axis of 35 the cylinder and adapted to receive wear plates which are retained in position by heads connected to the flanges of the cylinder. This manner of assembling the wear plates and heads is advantageous from a 40 manufacturing standpoint as there will be a minimum amount of machining.

My invention further aims to provide a 45 rotary pump including a rotor having pivoted pistons which are movable in and out of the rotor and when within the rotor provide practically a solid rotor, there being no 50 space or dead pockets to receive a liquid to be carried past the outlet and thereby reduce the efficiency of the pump. The packing associated with the pistons prevents liquid 55 from passing from the compression to the vacuum side of the pistons or blades and in this manner the pumping efficiency of the

rotor is materially increased and a pump of maximum power obtained. 55

My invention further aims to provide a simple, durable, inexpensive, and normally primed rotary pump which will be herein-after specifically described and then claimed, reference being had to the drawings, where- 60 in—

Figure 1 is a cross sectional view of the rotary pump;

Fig. 2 is a side elevation of the same, partly broken away and partly in longitudinal 65 section;

Fig. 3 is an end view of a detached rotor;

Fig. 4 is a side elevation of the same;

Fig. 5 is an end view of a detached piston;

Fig. 6 is a side elevation of the same, and 70

Fig. 7 is a cross sectional view of the piston.

In the drawings, the reference numeral 1 denotes a suitable base or foundation provided with a cylinder 2 having the upper 75 portion thereof formed with an inlet connection 3 and an outlet connection 4, these connections being tangentially disposed relative to the inner wall or chamber 5 of the cylinder.

The ends of the cylinder 2 are formed with peripheral flanges 6 having annular seats 7 for wear plates 8 which are set in said seats to close the ends of the chamber 5. The inner faces of these wear plates may be ground to present smooth and uninterrupted contact faces, and said wear plates are retained in the ends of the cylinder by heads 9 secured to the flanges 6 by screws 10 or other fastening means. The heads 9 are provided with longitudinally alining bearings 11 which are eccentrically disposed relative to the axis of the chamber 5, and journaled in the bearings 11 and extending through the wear plates 8 is a driven shaft 12, said shaft 95 extending longitudinally of the chamber 5 above the horizontal plane of said cylinder.

Mounted on the driven shaft 12 in the chamber 5 and between the wear plates 8 is a rotor 13 which is therefore eccentrically 100 disposed relative to the peripheral wall of the chamber 5, with the periphery of said rotor almost or practically in contact with said wall at a point between the inlet and outlet connections 3 and 4 respectively, thus 105 leaving a somewhat crescent shaped space or

liquid receiving chamber between the rotor and the lower portion of the cylinder 2 which space receives liquid from the inlet connection 3 to be transferred to the outlet connection 4.

The rotor 13 is provided with a plurality of curved pockets or slots 15 which extend longitudinally of the rotor and inwardly from its periphery with the ends of the 10 pockets communicating with sector-shaped recesses 16 in the end walls of the rotor. In the recesses 16 are pivot pins or trunnions 17 and loose on said pivot pins or trunnions are the hook shaped ends 18 of 15 side piston arms 19 integral with pistons or blades 20, said pistons being movable in and out of the pockets 15 as the arms 19 swing on the pins 17 in the recesses 16 with their ends contacting the wear plates 20 8 at the ends of the cylinder 2. The pistons or blades 20 are of segmental shape in cross section and each has a longitudinal slot or space 21 for a packing member or strip 22 made of any suitable material, such 25 as leather or any other suitable substance that may contact with the inner wall of the chamber 5 and insure a reasonably tight joint between the blades and the peripheral wall of the chamber.

30 The piston blades 20 are adapted to completely fill the pockets 15 when in retracted position and the packing 22 is made of a greater width than the width of the slots of said blades, so that the packing will 35 protrude beyond the inner and outer edges of the blades, and slightly beyond the ends thereof. This is best shown in Figs. 5, 6 and 7, also in Fig. 1, where it will be noted that the inner edge of the packing is bent 40 into contact with the rear wall of the pocket by the pressure of the fluid in said pocket, thus sealing the rear side of the pocket which is toward the vacuum or inlet side of the piston, so that fluid under compression 45 in advance of the pistons can not escape past them to the vacuum or inlet side, causing leakage and reducing the efficiency of the pump. Simple, cheap and efficient piston packing is thus provided, which packing is such that it will not wear the wall 50 of the slot and cause leakage and a tight joint is secured without the necessity for accurately machining either said wall or blade of the piston.

55 By making each piston blade with a face 25 to receive the packing strip 22 and providing a face plate 26 which is secured against the strip by rivets 27 passing through the plate strip and blade or otherwise connecting said plate to the body of the piston, a simple construction is secured 60 in which the packing 22 protrudes at all edges from the body of the piston to engage the wall of the chamber 5, and seal

the joint between the inner end of the blade 65 and the rear wall of the slot in the rotor.

As shown in Fig. 3 the walls of the 70 pockets 15 and a portion of the periphery 14 of the rotor may be provided with dove-tailed grooves 23 for anchoring lining 24 75 of Babbitt metal or the like to face these pockets so that the rotor may be die cast with the slots or pockets therein without the necessity for machining the walls of the pockets, as the Babbitt metal or lining may be cast in the pockets to provide the necessary smooth surfaces to engage the piston blades.

When the shaft 12 is driven the pistons 80 will be thrown outwardly by centrifugal force against the walls of the chamber 5 and as they travel away from the inlet, a partial vacuum will be formed causing the fluid to flow in through the inlet, which liquid, being trapped between the pistons, 85 will be transferred from the inlet connection 3 to the outlet connection 4, such transfer being continuous so that there may be an uninterrupted flow from the pump, especially when a head or column of liquid is 90 maintained at the outlet connection 4. As the piston blades are designed to substantially fill the slots in the rotor and their arms to fill the end recesses in the rotor, when the pistons come to the upper side of 95 the rotor during rotation and are forced to swing inwardly of the slots by their engagement with the wall of the chamber 5, all fluid is forced out of these spaces in the rotor as they pass the outlet and substantially all of the fluid will be forced out of 100 the outlet, making the pump very efficient as practically no fluid can be carried past the outlet.

105 The construction and arrangement of the cylinder casting, wear plates 8 and cylinder heads 9 is such that manufacture is greatly facilitated, in that the seats 7 for the plates are concentric with the axis of the bearings 11 for the shaft 12 which carries the rotor, and in securing the heads in place, the rotor may be adjusted in the cylinder accurately 110 so that its periphery will just contact the wall of the cylinder, at the upper side thereof and be perfectly aligned therein.

115 My pump is highly efficient for pumping oil or other liquids and on account of the compact arrangement of the various parts, it may be constructed upon a small scale so as to adopt it for use in small spaces, such 120 as the crank case of an automobile engine to form part of the lubricant circulating system of such engine. The uses of the pump are many and varied as it may be constructed in any size suitable to the work 125 or installation and for this reason I do not care to confine my invention to the precise construction and arrangement of the parts

shown, other than as defined by the appended claims.

What I claim is:—

1. A rotary pump wherein a rotor is formed with pockets extending inwardly from the periphery thereof and is mounted eccentrically within a cylinder with piston blades carried in said pockets and movable inwardly and outwardly of said pockets, a packing carried by each piston blade with a flexible edge portion of said packing projecting inwardly from the inner edge of the blade with said flexible edge portion engaging the rear wall of the pocket, to be held by fluid pressure against said wall and prevent leakage rearwardly in the direction of rotation of the rotor, past said blades.
2. A rotary pump wherein a rotor is eccentrically disposed within a cylinder having inlet and outlet connections, piston blades carried by said rotor, said rotor having pockets within which said blades are movable, said blades substantially filling said pockets when said blades are in retracted position, means pivotally supporting said blades for movement into and out of said pockets of said rotor, said rotor being formed with recesses to receive said means with said means substantially filling said recesses when said blades are in retracted position, and packing carried by each blade, said packing comprising a flexible strip having an edge portion projecting beyond the inner side of the blade and adapted to be flexed laterally by fluid pressure into engagement with the rear wall of the pocket for the piston to seal the joint between said piston and said wall and prevent leakage past the pistons rearwardly in the direction of rotation during the movement of said pistons.
3. A rotary pump as in claim 2 characterized in that the flexible strip is of fibrous material and formed with a thinned edge, the strip being secured in position by a face plate, the plate and strip being relatively positioned in such way that the thinned edge projects beyond the inner edge of the face plate at the inner side of the piston to form the portion of the strip to be flexed into engagement with the rear wall of the pocket.
4. In rotary pump formations wherein the stator member and rotor are of eccentric relation, and wherein the rotor carries a plurality of pivoted elements movable relative to pockets during the travel of the blade of each element in contact with the circular face of the stator member, the space between successive blades forming a chamber for receiving the fluid from the intake and delivering it to the outlet of the stator member, means carried by each element for preventing leakage from an advance to a rear chamber during the period of travel from the intake to the outlet, said means including a flexible formation carried by the element and having its end faces in contact with the wear plates of the stator and its outer face maintained in contact with the circular wall of the stator member by the travel of the rotor, said formation having a portion projecting from the face of the element opposite such outer contacting face of the formation, said projecting portion having a cross-sectional configuration such as to provide for flexibility thereof and produce a lip characteristic with such lip positioned to permit its contact with the rear wall of the pocket during movement of the element therewith and in presence of fluid pressure within the advance chamber.

In testimony whereof I affix my signature in presence of two witnesses.

FRED A. LEIGH.
